Patented Sept. 7, 1976

241,381

COMBINED CHECKBOOK WALLET AND ELECTRONIC CALCULATOR

Gary E. Garnier, San Jose, Calif., assignor to
National Semiconductor Corporation

Filed Feb. 21, 1975, Ser. No. 551,916

Term of patent 14 years

Int. Cl. D3—01

U.S. Cl. D87—3 A

Fig. 1

Fig. 2

Fig. 3

FIG. 1 is a perspective view of a combined checkbook wallet and electronic calculator showing my new design in a fully opened condition;

FIG. 2 is a front perspective view thereof; the exterior surfaces not shown being plain and unornamented with the exception of the perimetric stitching; and

FIG. 3 is a bottom plan view thereof in a closed condition.

I claim:

The ornamental design for a combined checkbook wallet and electronic calculator, as shown and described.
